UNITED STATES PATENT OFFICE.

SAMUEL NASH, OF WINNIPEG, MANITOBA, CANADA.

REMEDY FOR RHEUMATISM.

SPECIFICATION forming part of Letters Patent No. 328,507, dated October 20, 1885.

Application filed December 8, 1884. Serial No. 149,775. (No specimens.)

To all whom it may concern:

Be it known that I, SAMUEL NASH, of the city of Winnipeg, in the Province of Manitoba, Canada, gentleman, a subject of the Queen of Great Britain, have invented a certain new and useful Composition of Matter to be used as a Remedy for Rheumatism of the Human Body.

The object of the invention is to treat rheumatism of the human body.

The following specification of my composition consists of the following ingredients, combined in the proportions stated, viz: Haarlem oil, (balsam of sulphur, three pints; Barbadoes tar, one pint; crude oil of amber, one and one-half pint; oil of turpentine, eight pints; linseed-oil, four pints—mix them,) one and one-half dram; oil of juniper, one and one-half dram; oil of rosemary, five drams.

The ingredients are to be thoroughly mingled by agitation, and to be used according to the following directions: For an adult commence with two drops, and increase two more

every dose until sixteen drops are reached, then decrease two drops every dose until two 25 are reached again. For a child under ten years of age the same, but half quantities. In extreme cases the same, but doses from three to twenty-four drops. Repeat if necessary. To be taken the last thing at night and 30 the first thing in the morning.

What I claim, and desire to secure by Letters Patent of the United States, is—

The herein-described composition of matter to be used for treating rheumatism of the 35 human body, and being a compound consisting of balsam of sulphur, Barbadoes tar, crude oil of amber, oil of turpentine, linseed-oil, oil of juniper, and oil of rosemary in the proportions specified.

Dated this 27th day of November, A. D. 1884.

SAMUEL NASH.

In presence of—

ALEXR. LOZAM,
JOSEPH METCALF.
